CLAIM

The ornamental design for a dumbbell-shaped drink pitcher with integral straw, as shown and described.

DESCRIPTION

FIG. 1 is a top view of the dumbbell-shaped drink pitcher with integral straw according to my new design;

FIG. 2 is a front view thereof;

FIG. 3 is a right side view thereof;

FIG. 4 is a rear view thereof;

FIG. 5 is a left side view thereof;

FIG. 6 is a bottom view thereof.

FIG. 7 is a perspective view thereof; and,

FIG. 8 is a perspective view of the dumbbell-shaped drink pitcher with integral straw with its cap removed.
